TEXTILE FABRIC.

Specification of Letters Patent. Patented May 18, 1915.

Application filed January 2, 1915. Serial No. 317.

To all whom it may concern:

Be it known that I, FRANK G. MURCH, a citizen of the United States, residing at Methuen, in the county of Essex and State 5 of Massachusetts, have invented certain new and useful Improvements in Textile Fabric, of which the following is a specification.

This invention relates to textile fabrics and consists of a particular arrangement of 10 warp and weft threads of certain specified materials. The fabric is intended primarily for what is known as men's goods and more particularly for use as an outing cloth for garments of both men and women. Its purpose is to provide a cloth of peculiar brightness and characteristic luster. One which is cool in warm weather, which keeps its shape and which can be washed without losing its luster. In making this fabric, I prefer to 15 use a continuous strong cotton warp which may be of single or plural ply, preferably two ply. For the weft threads, I use preferably one pick of mohair and then a pick of silky fiber such as silk or of artificial silk, 20 preferably the latter. These mohair threads 25 should preferably be of combed fiber.

In the drawings, the figure shows an enlarged section of cloth of my construction.

A represents the cotton warp threads, C represents the mohair weft threads and D 30 the weft threads of silky fiber.

I claim:

1. A woven fabric consisting of a warp of two ply cotton threads and a weft having alternate picks of mohair and of artificial 35 silk.

2. A woven fabric consisting of a warp of cotton threads and a weft having picks of mohair alternating with picks of artificial silk.

3. A woven fabric consisting of a warp of cotton threads and a weft having picks of mohair and of silky fiber.

In testimony whereof I hereto affix my signature in presence of two witnesses.

FRANK G. MURCH.
